A. F. EELLS

DIAPHRAGM PUMP

Filed Oct. 25. 1922

Inventor:

Albert F. Eells

UNITED STATES PATENT OFFICE.

ALBERT F. EELLS, OF ROCHESTER, NEW YORK.

DIAPHRAGM PUMP.

Application filed October 25, 1922. Serial No. 596,780.

To all whom it may concern:

Be it known that I, ALBERT F. EELLS, a citizen of the United States, and resident of Rochester, in the county of Monroe and 5 State of New York, have invented certain new and useful Improvements in Diaphragm Pumps, of which the following is a specification.

My invention relates to diaphragm pumps 10 and it has for its object to improve the construction of pumps of this class so as to enable more water to be raised at each stroke; to obtain maximum efficiency and to provide for raising the water to a greater height 15 than has been possible with pumps of this kind as heretofore constructed. It is also an object of my invention to reduce to the minimum the strain and wear imposed upon the diaphragm itself thus lengthening the life 20 thereof. A further object of my invention is to provide for convenient and accurate assembling of the parts, particularly the diaphragm, as well as for correctly positioning the diaphragm when substituting a 25 new one, or angularly adjusting the diaphragm from one position to another, as is frequently necessary with pumps of this kind and usually performed by unskilled persons.

With these objects in view I propose to 30 provide a two-part housing for the diaphragm between which the margin of the diaphragm is immovably clamped and confined, one of the sections of this housing having a supply conduit communicating 35 with it that extends downwardly to the water that is to be raised, and the other section of the housing having a delivery conduit communicating with it which extends upwardly to the point of delivery. Within 40 the delivery conduit is arranged a rod or the like connected at its lower end with the diaphragm and at its upper end with any suitable operating means, such as the usual lever, or with an engine. Thus each suction 45 stroke of the diaphragm also positively lifts the column of water within the upper conduit at the same time that water is elevated within the lower conduit by air pressure, thereby greatly increasing the possible 50 maximum lift which is limited only by the force available for working the pump.

Another feature of my invention consists 55 in providing two metal members which may be in the form of rings or disks, one at each side of the diaphragm, together with means for clamping said members and the dia-

phragm firmly together, the sides or faces of said members adjacent the diaphragm being beveled, crowned, rounded, or otherwise shaped, so that only the middle portion of 60 the diaphragm is clamped between them, leaving the outer portion thereof free to 65 belly or swing in opposite directions between the oppositely beveled or rounded faces of the members. Thus upon the up stroke of 65 the diaphragm, the latter is forced to conform to the shape of the beveled or rounded lower member which acts to force the free portion of the diaphragm upward further than has heretofore been the case, and upon 70 the down stroke the upper member acts in like fashion to push the free portion of the diaphragm further downwards than has heretofore been the case. For the best effects these members may be made only 75 slightly less in width or diameter than the width or diameter of the diaphragm chamber. As will be clear these two members not only serve to increase the capacity of pumps of this kind by reason of the fact that they 80 serve to fully distend the diaphragm at each end of its stroke, but they also serve to support and reinforce the diaphragm thus relieving the latter of injurious strains and thereby lengthening its life. Of course only 85 one member disposed upon the under side of the diaphragm, may be employed if desired, with beneficial effect, but the maximum advantage is obtained by the use of two members, one at each side of the diaphragm. 90

Another feature of my invention consists in constructing a pump of this kind with a two-part diaphragm housing between which the margin of the diaphragm is clamped, the bottom section of said housing being 95 constructed with a pair of diaphragm positioning pins occupying two of our equally spaced apertures provided through the marginal portion of the diaphragm. The advantage of this construction is that the pins 100 engaging the holes in the diaphragm serve to accurately position the latter in assembling the structure and at the same time the extra pair of holes in the diaphragm permit of adjustment of the diaphragm angularly 105 when the upper portion of the apparatus is angularly adjusted as is frequently necessary in practice.

In the accompanying drawings:

Figure 1 is a side elevation, partly broken 110 away, of a diaphragm pump constructed in accordance with my invention.

Figure 2 is a central vertical sectional view through the diaphragm housing of the pump shown in Fig. 1.

Figure 3 shows, in plan the diaphragm 5 and a portion of the lower section of the diaphragm housing.

Having reference to the drawings, 5 and 6 represent the two sections of the two-part diaphragm housing referred to above, 10 said sections being herein shown as constructed with flanges upon their outsides from which project slotted lugs 6. The lugs 6 of the two sections register and the latter are firmly secured together by means of 15 bolts 16 occupying the slots of lugs 6. The upper section 5 has its top wall formed with an interiorly threaded port into which is screwed the lower end of an upwardly extending delivery conduit 7 whose upper end 20 is screwed into the base of the pump head 9 that may be secured, as usual, in position upon the deck of the vessel or upon any other suitable support. The lower section 6 has its bottom wall made with an interiorly 25 threaded outlet port into which is screwed the threaded upper end of a supply or suction conduit 8 that extends downwardly into the hold of the vessel, or into the body of water that is to be raised by the pump.

30 The diaphragm of the pump is shown at 3 and has its marginal portion clamped securely between the two sections 5 and 6 of the housing. At its middle this diaphragm is formed with a port 17 surrounded by an up- 35 standing flange 18 integral with the dia- phragm, the latter being made as usual from rubber, leather or any other suitable and flexible substance. The top of this upstand- 40 ing flange 18 serves as a seat for a down- wardly closing check valve 12 pivotally mounted upon the diaphragm, or upon the diaphragm structure, in the usual well known fashion, not illustrated here. Upon the top side of the diaphragm 3 is a dia- 45 phragm supporting and reinforcing member which has that side thereof which abuts the diaphragm crowned, rounded or other- wise made convex, to conform to the shape of the diaphragm when fully distended at 50 the limit of its downward movement. Upon the under side of the diaphragm is a similar diaphragm reinforcing and supporting member 2 whose top side is a counter part of the under side of the upper member 1. 55 These two members 1 and 2 are clamped securely to the diaphragm and, as will be clear from Figure 2 of the drawings, a consider- 60 able portion of the diaphragm between the marginal portion thereof that is clamped between the sections 5 and 6, and the middle portion, is left free to be flexed back and forth when the pump is operated. It will 65 also be clear that this free flexed portion of the diaphragm is confined within a more or less V-shaped channel which the two mem-

bers 1 and 2 provide between them near their peripheries, and that said flexed portion of the diaphragm is free to swing back and forth within this V-shaped channel. It is to be noted further, that the members 1 70 and 2 are only slightly less in width or diameter than the interior of the diaphragm chamber and therefore, when the diaphragm has been moved to the limit of its movement in either direction, the member 1 or 2 that is 75 upon the concaved side thereof acts to fully distend the diaphragm to the limit of its slackness. In pumps of this kind as heretofore constructed the free or flexed portion of the diaphragm between its clamped 80 marginal portion and the clamped middle portion would tend to assume an upwardly crowned shape upon the down stroke and to assume a downwardly curved or convex shape upon the up stroke, each shape being 85 maintained to the end of the stroke. On the other hand with my improved construction the member 1 acts during the down stroke of the diaphragm to fully distend the diaphragm downwardly expelling 90 through the port 17 a greater amount of water than heretofore. Also upon the up stroke the member 2 acts to fully distend the diaphragm upwardly thus increasing the lifting action and continuing the same at its 95 maximum to the very limit of the up stroke. The sudden termination of the movement of the diaphragm when it reaches the limit of the up stroke while the column of water is in motion upwards, results in a con- 100 tinuation of the upward flow for an appreciable period of time after the upward movement of the diaphragm has ceased owing to the momentum of the column of water.

The diaphragm 3 is made near its middle 105 with two holes 19, 19 that register with holes 20 provided through the members 1 and 2. These holes are provided to accommodate threaded shanks 21 forming part of a yoke 10, the two members and the dia- 110 phragm being clamped rigidly together and to the yoke by means of nuts as shown. The yoke 10 has fastened to it the lower end of a connecting rod 11 that extends up- 115 wardly through the conduit 7. The upper 120 end of this rod 11 is adapted, as shown in Figure 1, to be connected with the usual hand operated lever (not shown) or with other means by which the rod is reciprocated.

Within the lower section 6 of the housing 120 is pivotally mounted a second downwardly closing check valve 13 constructed and operating as usual.

Upon the outside of section 6, and at op- 125 posite sides thereof, are provided two lugs 22 within each of which is permanently se- cured the lower end of a pin 4. Preferably said lower end is secured within the lug by casting the lug around the pin. Each pin 4 130 extends upwardly through one of four equal-

ly spaced apertures 14 provided through the marginal portion of the diaphragm 3, and has its upper end disposed within a hole or socket 15 provided in a lug cast upon the exterior of upper section 5. Each aperture 14 is formed through a tang or ear 22 provided at the periphery of the diaphragm and four uniformly spaced sockets 15 are provided on the upper sections 5 of the housing. It will therefore be clear that the diaphragm 3 and all of the parts of the apparatus above and connected with it may, through the construction just described, be angularly adjusted so as to occupy any one of four positions. This capacity for adjustment is particularly advantageous when incorporated in pumps otherwise constructed as heretofore.

What I claim is:

1. In a diaphragm pump, the combination of a two-part diaphragm housing, a diaphragm having its outer marginal portion clamped between the two parts of the housing, and means carried by one part of the housing and extended through openings in the diaphragm and in the opposed part of the housing, one part of the housing having pins rigid in the marginal edge thereof and means cooperating with said pins for angular adjustment of the diaphragm.
2. In a diaphragm pump, the combination of a two-part diaphragm housing, a diaphragm having its outer marginal portion clamped between the two parts of the housing, means carried by one part of the housing and extended through openings in the diaphragm and in the opposed part of the housing one part of the housing having pins rigid in the marginal edge thereof, and means co-operating with said pins for angular adjustment of the diaphragm relatively to one of the housing parts.
3. In a diaphragm pump, the combination of a two-part diaphragm housing, a centrally disposed diaphragm therein having a centrally disposed valve, diaphragm supporting and reinforcing members upon opposite sides of the diaphragm with their adjacent faces oppositely curved, a yoke carrying a connecting rod, means depending from and rigid with said yoke for securing said members to the diaphragm adjacent the central port therein, a valve adapted to seat upon the wall of the opening of the diaphragm, a piston head connected to said diaphragm and members adjacent the valve seat, pins rigid with one part of said housing and means cooperating with said pins permitting angular adjustment of the diaphragm relatively to one of the housing sections.
4. In a diaphragm pump, the combination of a diaphragm housing, pins rigid with one section thereof, means cooperating with said pins, a centrally disposed diaphragm there-

in having a centrally disposed valve seat, said pins and means providing for angular adjustment of the diaphragm, diaphragm supporting and reinforcing members upon opposite sides of the diaphragm with their adjacent faces oppositely curved, a yoke carrying the connecting rod, means depending from and rigid with said yoke and securing said members to the diaphragm adjacent a central port therein, a valve adapted to seat upon the wall of the opening of the diaphragm, and a piston head connected to said diaphragm and members adjacent the valve head, said housing being of separable sections between which the periphery of the diaphragm is disposed and means for angular adjustment of the diaphragm relatively to one of said sections.

5. In a two-part diaphragm pump, the combination of a diaphragm housing, pins rigid with one section thereof, means cooperating with said pins a centrally disposed diaphragm therein having a centrally disposed valve seat, said pins and means providing for angular adjustment of the diaphragm, diaphragm supporting and reinforcing members upon opposite sides of the diaphragm with their adjacent faces oppositely curved, a yoke carrying the connecting rod, means depending from and rigid with said yoke and securing said members to the diaphragm adjacent a central port therein, a valve adapted to seat upon the wall of the opening of the diaphragm, and a piston head connected to said diaphragm and members adjacent the valve head, said valve being centrally disposed with relation to and seated directly upon the diaphragm and means for angular adjustment of the diaphragm relatively to one of said sections.

6. In a diaphragm pump the combination of a two-part diaphragm housing; a diaphragm having its outer marginal portion clamped between the two sections of said housing and a pair of diaphragm positioning pins carried by the lower section of said housing, said diaphragm being formed with apertures through which said pins extend.

7. In a diaphragm pump, the combination of a two-part diaphragm housing; a diaphragm having its outer marginal portion clamped between the two sections of said housing and a pair of diaphragm positioning pins carried by the lower section of said housing, said diaphragm being formed with a plurality of pairs of apertures to receive said pins with provision for angular adjustment of the diaphragm relatively to said lower section.

In testimony whereof I have affixed my signature.

ALBERT F. EELLS.
